United States Patent Office

Des. 189,242
Patented Nov. 15, 1960

189,242

KEY CHAIN

Anthony B. Laganella, 1824 Dudley St., and Charles E. McMenamin, 554 Acorn St., both of Philadelphia, Pa.

Filed Nov. 5, 1959, Ser. No. 58,217

Term of patent 14 years

(Cl. D17—3)

Fig. 1 is a front perspective view of a key chain showing our new design;

Fig. 2 is a right side view thereof;

Fig. 3 is a left side view thereof;

Fig. 4 is a rear view; and

Fig. 5 is a three-quarter front perspective view thereof.

For convenience of illustration, the chain has been omitted from Figs. 2, 3, 4 and 5.

We claim:

The ornamental design for a key chain, as shown and described.
